UNITED STATES PATENT OFFICE.

BURT R. VAN VALKENBURG, OF OAKLAND, CALIFORNIA.

CRESCENDO DEVICE.

1,126,137.

Specification of Letters Patent.

Patented Jan. 26, 1915.

Application filed November 4, 1913. Serial No. 799,115.

To all whom it may concern:

Be it known that I, BURT R. VAN VALKENBURG, a citizen of the United States, residing at Oakland, in the county of Alameda and State of California, have invented certain new and useful Improvements in Crescendo Devices, of which the following is a specification.

This invention relates to automatic musical instruments of the organ type and has as its principal object the provision of a device for producing a crescendo effect by throwing successively into operation the different sets of pipes or reeds.

15 A further object of my device resides in the particular arrangement and combination of parts hereinafter described.

My device is used as an auxiliary to the regular organ stops and in no way interferes with the action of the latter. It may be placed on the instrument so as to be operated in any convenient manner, such as a knee stop of the usual form.

20 In the instrument wherein my device is used, the stops throw the various sets of pipes into operation by pneumatic means and my device provides a second and independent means for operating these pneumatic devices so as to produce a crescendo effect. This operation takes place regardless 25 of the position of the manually operated stops and those of the latter which are in operating position continue to operate after this device is returned to its "off" position.

30 The advantages and construction of my improved device will be fully understood from the following specification, and the attached drawings forming a part thereof.

In the drawings:—Figure 1 is a view in 35 elevation of an orchestrion showing the manner in which my device is attached thereto. Fig. 2 is a diagrammatic view showing the manner in which the device operates for one set of pipes. Fig. 3 is a view in side elevation of my device. Fig. 4 is a view in plan of the same. Fig. 5 is a view in section on the line 5—5 of Fig. 3.

Referring more particularly to the drawings and denoting corresponding parts in the several views by the same numerals of reference, 1 denotes in general the operating instrument having side cases 2 and 3 in which are located the various sets of pipes and reeds.

40 4 denotes a row of stops for throwing into action the different sets, one pipe chest of

which is shown at 5, and the herein described operation of this set it will be understood, applies to the other sets as well. As shown in Fig. 2, each of the stops 4 in the non-operating position closes an air inlet 6 from which a tube 7 leads to a three-way connecting block 8. A second branch 9 leads from this block to my improved device which is denoted in general by 10, while the remaining branch 11 leads to a valve 12. This valve is arranged in a vacuum chamber 16, which connects with a suitable suction device through tube 16^a, so that the admission of air through either tube 7 or 9 raises the diaphragm 13 and thus the valve 14. This places tube 15 in communication with the vacuum chamber 16 deflating the bellows 17. The movable side of the latter is provided with an extension 18 connected to a rod 19 passing into the wind trunk 22 which is adapted to open the hinged valve 20. This places the pipe chest 5 in communication with the air supply pipe 23 through the passageway 21.

Referring now to the device 10 shown in Figs. 3, 4 and 5, this consists of a flat strip 25 having attached to each end supporting brackets 26 which have laterally extending arms 27 by which the device is attached to the supporting structure. In strip 25 is a plurality of vertical holes 28 having angularly extending branches 29 leading to the side thereof and connected with tubes 9. It will be understood that there are as many openings 28 as stops 4 and that the block 8 is provided with the same number of three-way connections. These openings 28 are normally closed by a strip of flexible material 30 which is fastened to 25 adjacent one of the brackets as at 31. The other end of this strip is fastened in a roller 32 as indicated at 33. This roller is provided with an axle 34 pivotally mounted in slots 35 in the guide bars 36 which latter are slidably mounted in recesses 37 (see Fig. 5) in the sides of the brackets 26. A spring 38 on each bar 36 exerts downward pressure on axle 34 thus holding the roller in closer contact with the strip 25. Bars 36 are connected at the ends by cross pieces 40 and 41 and to the former is attached a spring 42 which restores the roller to its normal position, while to the latter is attached an operating rod 42' which in turn is connected to the operating means such as the knee bracket 43.

The operation of the device is as follows:

When bracket 43 is pressed, the guide bars 36 are moved in the direction of the arrow (Fig. 3) against the tension of spring 42. This causes the rotation of roller 32 which, as it moves along the base 25, rolls up the flexible strip 30 around its periphery and successively uncovers the holes 28, which may be arranged in any desired manner but are preferably arranged in pairs as is shown in Figs. 3 and 4. As each hole is uncovered the air is passed through the corresponding tube 9 to its valve 12 which is opened to allow the bellows 17 to deflate and thus open the valve 20, placing that set of pipes in communication with the air pressure.

The means by which the individual notes are played is not deemed necessary to show here, as the preferred manner of so doing is made the subject matter of another application.

From the above description it will be understood that while I have shown and described the preferred embodiment of my invention, that minor changes may be made without departing from the spirit thereof.

Having thus described my invention, what I claim is:

1. In a device of the character described in combination, a valve plate having a plurality of openings therein, brackets on the ends of said plate serving to retain said

plate in position, each of said brackets having formed thereon registering slots, horizontally disposed guides slidably mounted in said slots, a flexible strip adapted to cover said openings, and means revolvably mounted in said guides, and engaging said plate for moving said strip to successively uncover said openings, substantially as and for the purpose set forth.

2. In a device of the character described in combination, a valve board, a plurality of openings therein, a flexible strip covering said openings, one end of said strip being attached to said valve board, brackets mounted on the ends of said valve board, guide bars slidably arranged in said brackets, a roller revolvably mounted in slots in said guide bars and having the other end of said flexible strip attached thereto, spring means for holding said roller seated on said flexible strip, and means for moving said roller so as to wind the flexible strip thereon and successively uncover the said openings, as and for the purpose described.

In testimony whereof I affix my signature in presence of two witnesses.

BURT R. VAN VALKENBURG.
